UNITED STATES PATENT OFFICE.

THOMAS H. BRADLEY, OF LEXINGTON, KENTUCKY.

MOLDED FENCE-POST.

No. 801,845.

Specification of Letters Patent.

Patented Oct. 17, 1905.

Application filed May 26, 1905. Serial No. 262,241.

To all whom it may concern:

Be it known that I, THOMAS H. BRADLEY, a citizen of the United States, residing at Lexington, in the county of Fayette and State of Kentucky, have invented a new and useful Molded Fence-Post, of which the following is a specification.

This invention relates to molded fence-posts, and has for its object to provide a novel arrangement of stiffening-core embedded in the post to prevent breakage thereof. It is also designed to equip the post with improved means for connecting fence-wires thereto and to associate the fence-fastening means and the core in such a manner as to mutually brace one another, and thereby increase the strength and durability of the post.

With these and other objects in view the present invention consists in the combination and arrangement of parts, as will be herein-after more fully described, shown in the accompanying drawings, and particularly pointed out in the appended claims, it being understood that changes in the form, proportion, size, and minor details may be made within the scope of the claims without departing from the spirit or sacrificing any of the advantages of the invention.

In the accompanying drawings, Figure 1 is a side elevation of a post of the present invention having a plurality of fence-wires connected thereto. Fig. 2 is a vertical longitudinal sectional view taken through the post at right angles to Fig. 1. Fig. 3 is a fragmentary sectional view taken on the line 3-3 of Fig. 2. Fig. 4 is a detail perspective view of the stiffening-core. Fig. 5 is a view similar to Fig. 1, showing a modification. Fig. 6 is a similar view at right angles to Fig. 5 with parts broken away to illustrate the interior of the post. Fig. 7 is a detail perspective view of the core member employed in the form of post shown in Figs. 5 and 6. Fig. 8 is a perspective view of another form of core member.

Like characters of reference designate corresponding parts in each and every figure of the drawings.

The body 1 of the present post is molded from plastic material and given any suitable shape, the preferred form being rectangular in cross-section. Embedded centrally and longitudinally in the post is a metallic core 2 in the nature of a flat bar bent intermediate 55 of its ends in an inverted substantially U shape, with its extremities directed outwardly to

form flanges 3. In corresponding upright edges of the sides of the core there are alined notches or seats 4 for the reception of open-ended metallic tubes or sleeves 5, which intersect the body of the post transversely through its longitudinal center, with their ends flush with the opposite faces of the post. These sleeves or tubes fit snugly the seats or notches 4, and the material of the post-body snugly embraces the core and the sleeve, whereby the latter members are held in intimate engagement and tend to materially stiffen and strengthen the post, and thereby prevent cracking and breaking thereof. For each sleeve or tube 5 there is a wire fence-fastener consisting of a stem or shank 6, having its ends projected externally of the sleeve, with one projected end threaded, as at 7, for the reception of a nut 8, the other end 75 of the stem being formed into an upstanding hook 9, designed to receive a fence-wire 10, which is firmly clamped between the hook and the adjacent face of the post by adjustment of the nut 8.

A very important advantage results in the combination of the tubes 5, the bolts 6, and the nuts 8, bearing against the ends of the tubes, in that the post is not worn by the tightening of the nuts, and therefore a strong and durable securing of the fence-wires is insured.

From the foregoing description it will be understood that the core member 2 and the sleeves or tubes 5 are cast or molded with the body of the post, and these parts are therefore rigid within the post, and by reason of the fact that the sleeves and the core are in intimate engagement there is little or no liability of these members working loose within the post under the strain of the fence-wires. The post and the wire-fastening devices are of course completed in the original manufacture of the post, and therefore the base of the latter may be set in the ground and the fence-wire connected to the post by the hooked fastenings 6 without requiring any assemblage or preparation of the post. When the fence-wires become slack, the wire-fasteners 6 may be loosened, the wires stretched, and then the fasteners tightened, so as to effectually hold 105 the wires to the posts after the former have been stretched to the desired taut condition.

A post constructed in accordance with the present invention is practically indestructible by climatic conditions, fire, &c., and may be 110 manufactured and sold as an entirety, which materially facilitates the erection of a wire

fence, as the fence-wire fasteners are all assembled and in any event need only to be thrust through the sleeves 5 and have the nuts fitted thereto to be in condition for receiving 5 the fence-wires.

In the formation of the post the edge notches or seats 4 in the core 2 are advantageous in that the sleeves or tubes 5 may be readily inserted sidewise into the seats, which 10 materially facilitates the assemblage of these parts.

Under some conditions one or more of the wire-fastening devices 6 may be removed and the fence runner or wire passed through the 15 tube or sleeve 5 without changing the post in any manner whatsoever.

A slightly-modified arrangement of post has been shown in Figs. 5 and 6, wherein the core member only has been changed, said core 20 member 11 consisting of a metallic rod or bar which is bent into inverted substantially U shape, so as to straddle the fence-fastening devices, the extremities of the core being bent laterally outward to form shoulders or 25 projections 12, corresponding to the shoulders or projections 3 of the first-described form of core. As best indicated in Fig. 6, it will be noted that two core members 11 are employed. It will here be explained that a greater or less 30 number of core members may be employed, according to the size and requirements of the post.

Another form of core member has been shown in Fig. 8 and designated in general 13, 35 said core member having substantially the shape of the other core members, but is formed of barbed wire, preferably consisting of two twisted strands and barbs 14 engaged therewith, the barbs serving to rigidly anchor the 40 core within the cement body of the post, so as to prevent looseness therein, the extremities of the core of course being bent to provide projections or flanges 15, forming additional anchoring means.

45 Having fully described the invention, what is claimed is—

1. A molded fence-post having a substantially U-shaped metallic core embedded therein with corresponding edges provided with alined 50 notches, and open-ended tubes fitted sidewise

in corresponding notches with their ends flush with opposite faces of the post.

2. A molded fence-post having a core consisting of a flat metal bar bent intermediate of its ends into substantial U shape with corresponding edges provided with alined notches, and tubular open-ended sleeves fitted snugly 55 in corresponding notches with their ends flush with opposite faces of the post.

3. A molded fence-post having a core embedded therein and provided with edge notches, and a series of open-ended tubes fitted snugly 60 in the notches with their opposite ends flush with the opposite faces of the post.

4. A molded fence-post having a metallic 65 tube embedded therein with its ends open and at respective faces of the post, a stem member adjustable endwise through the tube with its ends projected externally of the post, one projected end of the stem being provided with a fence-engaging element, and a clamping member carried by the other projected end of the stem and bearing against the adjacent end of the tube. 70

5. A molded fence-post having an open-ended tube embedded therein with its ends at 75 opposite faces of the post, an endwise-adjustable stem fitted in the tube and projected at opposite sides of the post, one end of the stem being provided with a hook and its opposite projected end threaded, and an adjusting-nut fitted to the threaded end of the stem and bearing against the adjacent end of the tube.

6. A molded fence-post having an inverted substantially U-shaped metallic core embedded 85 therein with its opposite sides provided with a series of alined notches, a series of open-ended tubes fitting snugly in corresponding notches with their ends flush with opposite faces of the post, wire-engaging hooks having 90 their stems extending through the respective sleeves, and adjusting-nuts fitted upon the stems.

In testimony that I claim the foregoing as my own I have hereto affixed my signature in 95 the presence of two witnesses.

THOMAS H. BRADLEY.
